AIR CONDITIONER

Don E. Dasher, Dayton, Ohio, assignor to General
Motors Corporation, Dayton, Ohio, a corpora-
tion of Delaware

Application October 28, 1936, Serial No. 108,025

2 Claims. (Cl. 257—3)

This invention relates to air conditioning systems in which the refrigerating apparatus is used for cooling the air in the summer time and is used for heating the air in the winter time.

An object of this invention is to provide a refrigerating system wherein the refrigerant within the system can be used for both cooling and heating.

A still further object of this invention is to provide a system in which a single heat exchange coil is utilized for both heating and cooling.

A still further object of this invention is to provide an air conditioning system having novel means for controlling the cooling in the summer time and the heating in the winter time.

Further objects and advantages of the present invention will be apparent from the following description, reference being had to the accompanying drawings wherein a preferred form of the present invention is clearly shown.

In the drawings:

Fig. 1 is a view, partly diagrammatic and partly cross-sectional, of an apparatus embodying features of my invention;

Fig. 2 is a diagrammatic view showing the circuit arrangement used with the apparatus shown in Fig. 1;

Fig. 3 is a view, partly diagrammatic and partly cross-sectional, of a modified arrangement of apparatus embodying features of my invention;

Fig. 4 is a diagrammatic view showing the circuit connections used with the apparatus shown in Fig. 3;

Fig. 5 is a diagrammatic view of a slightly different type of control which may be used with the apparatus shown in Figs. 1 and 3.

In this invention, the air conditioning unit may be of the self-contained type, or it may be of the type in which a heat exchange unit is mounted within the room, the air of which is to be conditioned, and the remainder of the apparatus is located in a separate room such as a room in the basement. For purposes of illustrating my invention, I have shown only one heat exchange unit placed in a room; whereas, in actual practice, a number of units may be mounted in a number of rooms with a central plant for supplying attemperating fluid to the heat exchange units mounted in the various rooms.

In Fig. 1 of the drawings, I have shown a compressor unit 10, a motor 11 for driving the compressor, a heat exchange coil 13 located outside of the enclosure and a complementary heat exchange coil 14 supported in a cabinet 15 located within the enclosure 16. A by-pass 17 is

provided between the high side of the compressor unit and the low side, and a three-way valve 18 is inserted at the juncture of the by-pass 17 and the high side line. As shown in the drawings this valve may be set so that fluid circulating between the complementary heat exchange units may flow directly from the one heat exchange unit to the other without passing through the compressor unit. A pipeline 19 connects the heat exchange member 14 with the usual sump 20. A solenoid valve 21, a conventional type of restrictor valve 22 and a manually operated valve 23 are inserted in the line 19. A by-pass 24 having a valve 25 is provided for bypassing fluid around the valves 21, 22 and 23. A pressure responsive bellows 28 is connected into the line entering the low side of the compressor for operating the switch 29 so as to start and stop the motor in response to the low side pressure in a manner well known in the art. A manual valve 30 is also placed in the low side line. A coil 31 is in thermal exchange relationship with the coil 13. Steam or hot water is supplied to the coil 31 through the pipe line 33 in which is placed a solenoid valve 34. Steam or hot water leaves the coil via the pipe line 35. Three-way valves 36 and 37 are placed in the steam line so that when the apparatus is intended to be used for cooling purposes, cold water may be supplied through the pipe line 38 and leave via pipe line 39. A bimetallic thermostat member 40 is placed within the room for controlling the operation of the conditioning apparatus. Contact 41 which is carried by the metallic thermal member 40 engages contact 42 upon the temperature in the room reaching a predetermined high and engages the contact 43 upon the temperature within the room reaching a predetermined low. A fan 45 causes air to flow in through the opening 46 over the heat exchange coil and out through the opening 47 into the space 16.

Whenever it is desired to heat air for the enclosure, manually operated valves 23 and 30 are closed, valve 25 is opened, and the three-way valves 18, 36 and 37 are placed in the position shown in Fig. 1. It is apparent, therefore, that the compressor unit is no longer in fluid flow relationship with the heat exchange units 50 and the solenoid valve 21 together with the restrictor valve 22 are shunted out of the circuit. Upon contact 41 engaging the contact 43, the solenoid valve 34 will be operated so as to supply steam or hot water to the coil 31. With the valves set as indicated hereinabove, fluid circu-

lating through the coil 13 will be heated by steam or hot water flowing through the coil 31. The steam will heat the fluid in the coil 13 and cause the same to rise to the coil 14, thereby causing the coil 14 to become a heater. The gas will condense in the coil 14 and drain back to the sump 20. When no more heating is necessary, the contacts 41 and 43 will separate and cut off the steam supply at valve 34. When it is desired to cool the air for the room, the hand valves 23 and 30 are opened, the valve 25 is closed, the valves 36 and 37 are set so as to supply cold water to the coil 31, and the three-way valve 18 is set so as to block off the by-pass 17 and cause the compressed refrigerant leaving the compressor to flow into the condenser coil 13. The solenoid valve 21 which is in circuit with contacts 41 and 42 will then control the flow of refrigerant from the sump 20 to the evaporator 14, and the switch 29 will start and stop the compressor unit in the usual well known manner. The refrigerant fluid employed may be the same as that employed in the usual refrigerating systems. By using both the thermostat 40 and the pressure operated switch 29 for controlling the cooling, it is possible to arrange a plurality of evaporators in parallel with the liquefying unit. When a plurality of evaporators are used, a solenoid valve such as 21 will be provided for each evaporator and a single pressure responsive switch 29 will be used in the suction line adjacent the compressor so as to stop the compressor only at such times when none of the evaporators are in use.

A manual switch 48 as shown in Fig. 2, is placed in the main circuit so as to completely shut down the fan, the compressor and the control means for the solenoid valves. A second manual switch 49 may be opened if it is desired to operate the fan 45 only. A manually operated switch 50 is also placed in the compressor motor circuit in case it is desired to shut down the compressor during the winter months or during any other desired time. Any conventional furnace may be employed for supplying the steam or hot water to the coil 31. For that reason, I have not shown any specific furnace. While I have shown manual means for changing over from heating to cooling, it is obvious that automatic means may equally well be employed for this purpose.

In the modification shown in Fig. 3, somewhat the same arrangement is shown except that fully automatic means are disclosed for changing over from winter to summer conditions. In describing the apparatus shown in Figs. 1 and 3, the term "summer" is used to designate any time of the year when cooling is desired; whereas the term "winter" is used to designate those periods when heating is desired. Obviously, during spring and fall especially, frequent changeovers from heating to cooling will take place.

Like reference characters have been used to designate like parts in Figs. 1 to 3.

Except for the arrangement of the fan within the casing 15 and the automatic control means, the apparatus in Fig. 3 is similar to the apparatus in Fig. 1, and for that reason will not be described in detail except for the control means. In the modification shown in Fig. 3, the fan 45 is placed beneath the heat exchange coil 14, so as not to subject the fan to the hot air passing over the coil 14. Baffles 55 have been provided so as to prevent condensate from dripping on the fan 45.

In Fig. 3 I have shown a furnace which might equally well be used with the apparatus shown in

Fig. 1. Burner 56 which is supplied with fuel through line 57 is used for heating the water within the boiler 58. The usual type of thermostatic control means 59 controls the flow of fuel through the valve 60 so as to maintain the proper conditions within the boiler. Reference numeral 61 designates the usual pilot. In order to insure the maintenance of a proper water level within the boiler, float means 62 have been provided for opening the valve 63 in the water supply line 64 upon the water level becoming low and the same float is used for opening the valve 65 so as to permit excess water to drain out through drain 66. While I have shown a single float for maintaining proper liquid level within the boiler, a plurality of floats or any other suitable arrangement may be employed for maintaining the proper liquid level.

Referring now to Fig. 4, reference numeral 70 designates an outside thermostatic means for closing the switch 71 when the outdoor temperature is sufficiently high to require cooling. Upon the outdoor temperature dropping below a predetermined temperature, the switch 72 will tend to close. Inasmuch as it frequently happens that the outdoor temperature might be high, for example, but the indoor temperature might still be low enough so that there would be no need for the operation of the cooling apparatus, I have shown a latch means 73 for latching the switch 71 in the open position until the indoor temperature becomes sufficiently high to warrant the operation of the cooling equipment. The latch 73, therefore, is operated by means of a thermostat 74 located within the enclosure. During normal operation, fluctuations in the indoor temperature will not interfere with the switch 71 so long as the outdoor temperatures are high enough to hold the switch closed.

Similarly, in order to prevent the operation of the heating equipment before heating is required within the enclosure, I have provided a second latch 75 which latches the switch 72 in the open position until the indoor temperature is low enough to require heating. The latch 75 is controlled by means of an indoor thermostat 76. The temperatures at which the switches 71 and 72 operate are selected so that only one switch is in the closed circuit position at any given time. In order to be able to render all of the equipment inoperative at will, I have provided a pair of manual switches 77 and 78 for opening the control circuits. In order to simplify the circuit diagram, each separate solenoid has been shown as operating a separate valve, whereas, in fact, each of the three-way valves is operated by a pair of solenoids. When the manual switch 78 and the automatic switch 71 are both closed, the circuit for the solenoid 80 will be closed with the result that the three-way valve 137 will be set to supply cold water to the coil 31, and the circuit leading to the solenoid 81 will also be closed with the result that the three-way valve 118 will be set to deliver refrigerant from the compressor to the coil 13. Likewise, the circuit to the solenoid 83 will be closed so as to set the three-way valve 136 in position for the flow of cooling water, and the circuit leading to the solenoid 84 will be closed so as to make the valve 121 responsive to the thermal switch 40. The circuit leading to the solenoid 85 will also be closed with the result that the valve 130 will be opened.

Upon the temperature conditions outside changing so that heating will be required, and upon the indoor temperature dropping sufficiently

to release the latch 75, the switch 72 will be closed. The closing of switch 72 causes the circuit leading to the solenoid 85 to close, thereby energizing the valve 118 so as to shunt the compressor out of the circuit. The circuit of the solenoid 87 will also be closed with the result that the valve 125 will be opened so that fluid may freely flow from one heat exchanger to the other without passing through the restrictor valve 22 and the solenoid operated valve 121. The circuit for the solenoid 88 will, likewise, be closed with the result that the three-way valve 137 will be shifted so as to permit the flow of steam through the coil 31. The circuit for the solenoid 89 will be closed with the result that the three-way valve 136 will be set so as to permit the flow of steam through the coil 31. Likewise, the circuit will be closed to the solenoid 90 so as to fully open the valve 91 in the fuel supply line. The closing of the switch 72 also energizes the solenoid 92 which opens the valve 134 in the steam line, provided the circuit is closed between contacts 41 and 43.

In order to regulate the flow of cooling water when the unit is used for cooling purposes, I have provided the usual form of valve 100 which is responsive to the pressure in the line leading from the compressor to the condenser 13. The thermostatic control means 40, which I have described hereinabove, in connection with the apparatus shown in Fig. 1 and also the apparatus shown in Fig. 3, may be replaced by means of a slightly modified control apparatus shown in Fig. 5. The operation of the conditioning unit may be made responsive to the effective temperature in the enclosure 16. The term "effective temperature" is a term now well known in the air conditioning art. An instrument approximating in responsiveness in effective temperature may be used to control the solenoid valves shown. Thus, a relative humidity responsive member 151 made of wood or the like operates a lever 152 which is connected to a rotatable base 153 upon which is mounted the bimetallic thermostat 154. As the relative humidity changes, the base 153 is slightly rotated about the fulcrum 153a and thus the combination dry-bulb temperature and relative

humidity conditions both are effective on a control to close the contacts which govern the operation of the solenoid valves. A suitable rotatable knob 156 may be provided for turning a screw 5 which adjusts the position of the relative humidity responsive member 151 to vary the effective temperature at which the instrument opens and closes the contacts.

With applicant's arrangement, the apparatus 10 operates like any air conditioning system under summer conditions and in the winter, the valves are all turned to by-pass the compressor and expansion valve and admit steam through the water coil 31. The steam passing through the water 15 coil 31 heats the refrigerant in the heat exchange coil 13 and causes the same to rise to the heat exchange coil 14 with the result that the heat exchange coil 14 becomes a heater. This system, therefore, eliminates the use of a special coil for 20 winter heating.

While the form of embodiment of the present invention as herein disclosed constitutes a preferred form, it is to be understood that other forms might be adopted, all coming within the 25 scope of the claims which follow.

What is claimed is as follows:

1. In a combination adapted for conditioning air for an enclosure, apparatus for conditioning air for said enclosure comprising a compressor 30 and a plurality of heat exchange units connected in fluid flow relationship, means responsive to the psychrometric condition of the air outside said enclosure for rendering said compressor inoperative, and means for circulating a heating medium 35 in thermal exchange relationship with one of said units while said compressor is inoperative.

2. Air conditioning apparatus for an enclosure comprising a first heat exchange unit, a second heat exchange unit, changeover means for causing either one of said units to reject heat picked up by the other of said units, means responsive to the condition of outdoor air controlling said changeover means, and means responsive to the condition of air in said enclosure preventing said 45 changeover under a predetermined condition.

DON E. DASHER.
